UNITED STATES PATENT OFFICE

2,283,522

ABRASIVE DEVICE FOR CLEANING STILL
TUBES AND THE LIKEHermon G. Weinland, Springfield, Ohio, assignor
to Norton Company, Worcester, Mass., a corporation of Massachusetts

Application April 16, 1941, Serial No. 388,859.

8 Claims. (Cl. 51—170)

The invention relates to a tube cleaner designed for removing encrustations from the interior of tubes or boilers, stills, or the like.

One object of the invention is to provide a self-feeding tube cleaner of increased efficiency. Another object of the invention is to combine an automatic feed with an abrasive tube cleaner. Another object of the invention is to provide a tube cleaner feeding device which shall not score the tube. Another object of the invention is to provide a rapid feeding efficient tube cleaner producing a smooth and polished surface upon the tube. Another object of the invention is to improve upon the tube cleaner of my prior copending application Serial No. 321,951, filed March 2, 1940. Other objects will be in part obvious or in part pointed out hereinafter.

The invention accordingly consists in the features of construction, combinations of elements, arrangements of parts, and in the several steps and relation and order of each of said steps to one or more of the others thereof, all as will be illustratively described herein, and the scope of the application of which will be indicated in the following claims.

In the accompanying drawing illustrating one of many possible embodiments of the mechanical features of this invention,

Figure 1 is an axial sectional view of a still tube showing the tube cleaner of the invention located therein, illustrated in elevation;

Figure 2 is an axial sectional view of the tube cleaner head, showing the parts on an enlarged scale;

Figure 3 is an axial sectional view of the tube cleaner head, showing the parts on the same scale as Figure 1, the plane of the section being 90 degrees angularly removed from the plane of the section of Figure 2; and

Figure 4 is a front elevation of the tube cleaner head, the parts being shown on the same scale as Figure 2.

As conducive to a clearer understanding of the present invention, it is noted that in the operation of stills for cracking petroleum and for fractionating the higher hydrocarbons, the still tubes become encrusted with a carbonaceous deposit which is often very hard. Such encrustation not only decreases the capacity of the tube but also materially decreases its thermal conductivity and, therefore, it has been customary to clean out the encrustation from these tubes. For this purpose there have been provided air motors mounted on the ends of heavy hoses and driving divers forms of steel cutters.

The air motor and the cutters would be introduced into the tube to be cleaned. With the use of such tools various difficulties have been encountered, especially the injury of the still tube by the steel cutters, especially when the operator left the cutters in action in one particular place. Furthermore, it has been found necessary frequently to renew or sharpen the steel cutters.

Referring now to the drawing and first to Figure 1, a still tube to be cleaned of encrustation is indicated at 10, the encrustation of hard carbon or similar material being indicated at 11. The tool of my invention may be mounted on 15 the end of a suitable air turbine 12 which is energized by compressed air passing through a rubber hose 13. Such air turbines 12 mounted on the end of the hoses 13 are now readily available and will not, therefore, be particularly described, and any other prime or secondary mover 20 may be provided within the scope of the present invention. Such air turbines are capable of revolving a cleaning tool at speeds of the order of 1000 to 3500 R. P. M.

Still referring to Figure 1, at the end of the turbine, opposite the hose 13 is the driven spindle 14. This, as is customary, is drilled and tapped and fitted to a threaded clevis stud 15 which is connected to another threaded clevis stud 16 by 30 means of a link 17, these three parts constituting a universal joint.

Referring now to Figures 1, 2 and 3, I provide a nut 20 having a threaded bore 21 of small diameter and a threaded bore 22 of larger diameter. The threaded clevis stud 16 fits in the bore 21. I further provide a head comprising mating parts 23 and 24 having semi-cylindrical threaded portions 25 and 26 which together fit in the larger threaded bore 22 of the nut 20. The mating parts 23 and 24 are removably held together by three pins 27 fitting into appropriate holes 28 as shown. When the nut 20 is screwed onto the pair of semi-cylindrical portions 25 and 26, the mating parts 23 and 24 are locked together and form a rigid head for the mounting of the abrasive sticks to be described.

As shown in Figures 2 and 4, the head 24 is a cylinder with a portion thereof cut out by parallel chord planes, thus leaving projecting ends 30 and 31 which together form a fork. I provide a pair of parallel holes 32 and 33 in the projecting ends 30 and 31, the hole 32 in the end 30 being opposite the hole 32 in the end 31, and the hole 33 in the end 30 being opposite the hole 33 55 in the end 31. These holes or bores 32 and 33

constitute journals for the reception of trunnion pins 35, see especially Figure 3. The trunnion pins 35 are inserted into the holes 32 and 33 as the mating parts 23 and 24 are assembled. The trunnion pins 35 may be made of steel, as preferably is the head 23, 24 and the nut 20, and the trunnion pins 35 are embedded in and project from a pair of abrasive sticks 40. One end of each abrasive stick 40 is preferably rounded over as shown at 38 and a shaped rubber insert 39 is provided which has the effect of cushioning vibrations.

For the manufacture of the sticks 40, I may proceed as follows: Taking a quantity of silicon carbide abrasive in coarse grit size, for example 10 to 16 mesh grit size, and placing it in a mixing pan, I add furfural and mix until each granule is coated with furfural. I mix together a quantity of "A" stage phenol formaldehyde, abrasive fines and quick lime. I add this mixture to the mixing pan while continuing the mixing. I then add a quantity of neutral creosote oil and continue the mixing until the creosote oil has been thoroughly distributed throughout the mass of ingredients in the pan.

The "A" stage phenol formaldehyde is preferably permanently fusible solid phenol formaldehyde resin with sufficient hexamethylene tetramine to harden it. The abrasive fines may be very fine particles of any suitable abrasive, for example silicon carbide or aluminum oxide in grit sizes of the order of 400 to 600 mesh grit sizes. As a specific example of proportions for a suitable stick, I may make up an abrasive structure as follows:

	Per cent by volume
Abrasive	58
Bond	34
Pores	8

In the foregoing the "bond" comprises "A" stage solid resin 50% by weight, alumina fines 40% by weight and quick lime, CaO, 10% by weight. I may use 65 cubic centimeters of furfural and 25 cubic centimeters of creosote oil per pound of the above "bond."

The foregoing is given as an illustrative example only but it is noted that there is thereby formed a hard abrasive structure of slight porosity. By reason of the incorporation of the abrasive fines in the bond, the bond itself is quite tough.

So far as the particular bonding ingredients are concerned and the proportions thereof, I may vary the foregoing widely and, in fact, other bonds besides phenol formaldehyde may be used, such as rubber, shellac and the like. But I have found that of the common abrasives now known, only silicon carbide is satisfactory and I also find that the abrasive structure should be hard and dense.

I provide suitable molding equipment to form sticks of the general shape shown in Figures 1 to 4 inclusive which may be in general described as rectangular parallelopipeds. Preferably the outer or cutting side of the sticks is formed to provide initially a raised portion 41 joined to two bevelled portions 42, giving to each stick a pair of cutting edges 43 and a pair of cutting edges 44. But other shapes may be adopted. I mold the trunnion pins 35 into the sticks 40 at one end thereof, as shown, preferably providing metal washers 45 to locate the trunnions 35 and to transfer the thrust to a wide area of contact. Into the sticks 40 I mold steel wires 46 which

may be located as shown. I have found that a pair of hairpin shaped wires 46 for each stick is satisfactory. Preferably these pass around the trunnions 35 and at least one end of each wire 46 extends close to the outer surface of the stick 40 which is adjacent the tube 10 when the stick is being used.

So far as already described, the parts and features of the tube cleaner are the same as described in my prior copending application Serial No. 321,951. However, the nut 20 hereof has a different shape and according to the present invention I provide self-feeding means to feed the tool and the turbine 12 along the still tube 10. According to the present invention this self-feeding means may take the form of circular racks 50 loosely mounted on pins 51 and which are somewhat loosely mounted in bores 52 and 53 in the nut 20, which bores are separated by recesses 54 provided in the nut 20 to receive the circular racks 50. The bore 53 is slotted in a radial direction to permit radial adjustment of the racks 50 to slight variations in the diameter of the tube 10. The axes of the pins 51 are inclined to the axis of the tool, so that a feeding movement is given thereto by the gripping of the wall of the still tube 10 by the teeth 56 of the circular racks 50. Preferably I provide a plurality of racks 50, for example, three as shown. By making the racks loose on the pins and the pins loose in the holes, wear is reduced, there being two points of rotation. I provide a large washer 58 locked in place by the clevice stud 16 to limit the pins axially in one direction. For removal of the pins 51, holes 60 extending from the outside of the nuts 20 to the threaded bore 22 and in front of the pins 51 may be provided. As shown in Figure 1, the holes 52 are slightly offset from the holes 60, so the pins 51 cannot move axially in the other direction.

Referring now to Figure 1, a particular circular rack 50 is shown in elevation. It has an inclination of a few degrees to the axis of the tool, as will be readily seen. The circular rack 50 may be said to be "skewed" to the axis of the tool. The skew of each circular rack 50 to the main axis of the tool is the same. The racks are skewed in the same angular direction. The tool of the invention rotates counterclockwise in Figure 4, so in Figure 1 the circular rack 50 is moving downwardly. Its teeth 56 come to a broad point, so it frictionally grips the steel of the tube 10, and because the point is broad there is no cutting action. The abrasive sticks 40 clean out the still tube and polish it, leaving a smooth surface therein which is so important in the oil cracking industry, while owing to the use of a circular rack, the propelling device feeds the tool along the still tube without scoring the tube and the maximum gripping and propelling effect is obtained with the minimum of result upon the tube itself.

Considering now the operation of the device, the air turbine 12 is introduced into the tube 10 by means of the hose 13 in the usual way and the air is turned on. Sticks 40 cut the encrustation 11 and as the sticks wear away they move apart under the influence of centrifugal force. The sticks 40 are always pressing against the encrustations by reason of the centrifugal force, thus providing a satisfactory abrading pressure and at the same time causing the encrustation 11 to be evenly removed. That is to say, by reason of the fact that the sticks tend to swing 70 apart on their trunnion pins 35, they press

against the encrustation 11 at all angular positions irrespective of whether the tool is in exact axial alignment with the tube 10 or not.

Whereas it may take from fifteen minutes to four hours to cut out hard encrustations with the metal cutters, abrasive sticks, according to my invention rarely require more than fifteen minutes to do the job, and sometimes will clean a tube in three or four minutes. In this particular work time is of great importance since the entire unit is shut down while the tubes are being cleaned.

I have found that the combination of the use of silicon carbide and the embedded wires 46 gives an abrasive which will cut the encrustation 11 without detrimentally cutting the tube 10. The exact reason for this I do not know, especially since theoretically the wires 46 should wear away faster than the abrasive and also silicon carbide should abrade the steel of the tube. Nevertheless the results have been observed in actual practice and confirmed by repeated tests. Within the scope of the present invention, other abrasive shapes may be used.

It will thus be seen that there has been provided by this invention an article and a method in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawing is to be interpreted as illustrative and not in a limiting sense.

I claim:

1. A tool for removing encrustations in still tubes and the like comprising a head adapted to be rotated about an axis, an abrasive stick mounted on said head, and a tube gripping member mounted for rotation on an axis skewed with respect to the axis of rotation of the head and connected to the head, whereby to feed the head and the abrasive stick in the tube.

2. A tool for removing encrustations in still tubes and the like comprising a head adapted to be rotated about an axis, means carried by the head to clean the tube, and a circular rack mounted for rotation about an axis skewed with respect to the axis of the head, said rack being connected to the head, whereby the rack grips the wall of the still tube and by reason of the skew feeds the parts in the still tube.

3. A tool for removing encrustations in a still tube or the like comprising a rotatable member, a plurality of rotatable members having tube gripping peripheries mounted for rotation with respect to said rotatable member on axes skewed with respect to the axis of rotation of the rotatable member, which axes are at equal distances from the axis of the rotatable member, whereby to feed the rotatable member in the still tube as it rotates, and an abrasive stick con-

nected to the rotatable member to be rotated and fed by it in the tube.

4. A tool for removing encrustations in a still tube or the like comprising an abrasive stick, means mounting the abrasive stick for rotation, and a member mounted on said means for rotation about an axis skewed with respect to the axis of rotation of the means and provided with a tube gripping periphery, whereby to feed the abrasive stick as it rotates in the tube.

5. A tool for removing encrustations in a still tube or the like comprising a first rotatable member, a plurality of rotatable members formed as circular racks whose peripheries are thus adapted to grip the inner wall of a tube without marring the wall of the tube, said members being mounted for rotation with respect to said first rotatable member on axes skewed with respect to the axis of rotation of the first rotatable member, which axes are at equal distances from the axis of the first rotatable member in the still tube as it rotates, and an abrasive stick connected to the rotatable member to be rotated and fed by it in the tube.

6. A tool for removing encrustations in a still tube or the like comprising a first rotatable member, a plurality of rotatable members having tube gripping peripheries mounted for rotation with respect to said first rotatable member on axes skewed with respect to the axis of rotation of the first rotatable member, which axes are at equal distances from the axis of the first rotatable member, whereby to feed the first rotatable member in the still tube as it rotates, and a pair of abrasive sticks mounted on parallel axes transverse to the axis of rotation of the first rotatable member, whereby the sticks will swing further apart as they wear away and centrifugal force will press them against the encrustation.

7. A tool for removing encrustations in a still tube or the like comprising an abrasive stick, means mounting the abrasive stick for rotation, and a member formed as a circular rack mounted for rotation on said means about an axis skewed with respect to the axis of rotation of the means whereby to feed the abrasive stick as it rotates in the tube without marring the tube.

8. A tool for removing encrustations in a still tube or the like comprising a pair of abrasive sticks mounted on parallel axes transverse to the axis thereof as a unit, means mounting the abrasive sticks for rotation about said axis whereby as the pair of sticks as a unit rotate about the said axis of the said means they will swing farther apart on their parallel axes and centrifugal force will press them against the encrustation, and a member mounted on said means supporting the sticks, said member being mounted for rotation about an axis skewed with respect to the axis of the said means, and said member being provided with a tube gripping periphery, whereby to feed the pair of abrasive sticks as they rotate in the tube.

HERMON G. WEINLAND.
